UNITED STATES PATENT OFFICE.

GEORGE LENOX CURTIS, OF NEW YORK, N. Y.

IMAGE-REFLECTOR.

1,260,341.

Specification of Letters Patent. Patented Mar. 26, 1918.

Application filed February 24, 1917. Serial No. 150,735.

To all whom it may concern:

Be it known that I, GEORGE LENOX CURTIS, a citizen of the United States, residing at New York, in the county of New York and State of New York, have invented certain new and useful Improvements in Image-Reflectors; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in obsergraphs, comprising an instrument adapted to be placed in an opening in a door or wall and affording means whereby a person within the house may see by reflection objects without and consists of a simple and efficient device of this nature having various details of construction, combinations and arrangements of parts which will be hereinafter fully described, shown in the accompanying drawings and then specifically defined in the appended claims.

I illustrate my invention in the accompanying drawings, in which:—

30 Figure 1 is a central vertical sectional view through the device as applied to an opening in a door.

Fig. 2 is an elevation of the device.

Fig. 3 is a top plan view.

35 Fig. 4 is a vertical sectional view showing a slight modification of the invention.

Reference now being had to the details of the drawings by letter, A designates a door having an opening B therein, which, preferably, has its opposite sides beveled as at D in order to widen the range of operativeness of the device. The opening has transparent closures designated by letters E and F. Fastened to the inner face of the door is a hood H, forming a covering for a rotatable, right angled frame I, carrying a reflecting mirror J. Said frame I has a stem I' projecting through a boss H' formed in said hood and has a finger wheel N secured to its upper end, the circumference of which is preferably milled and forming a convenient means to tilt the mirror frame. R designates a mirror frame in which a mir-

ror is mounted and which frame is pivotally mounted upon a pin T and, when not in use, 55 said mirror frame is adapted to be swung to the position shown in solid lines in Fig. 1 of the drawings and, when in use, to the position shown in dotted lines.

In Fig. 4 of the drawings, I have shown 60 a slight modification of my invention in which the door A' is provided with an opening A'', and O designates a casing which is fastened to the inner face of the door adjacent to the opening A'', and L designates a 65 mirror having a frame L' with a stem L'' journaled in a boss in said frame and having a thumb wheel L''' to rotate the mirror. A lens, designated by numeral M, is mounted in the frame L' and is positioned in the 70 opening A'' and through which the image is projected upon the mirror. A second mirror is designated by numeral P and is positioned underneath the mirror L and parallel thereto and in a casing P' containing an eye 75 piece S, said mirror P serving to reflect the image from the first mirror, to the eye piece S.

In operation, when the device is attached to a door frame or wall of a building, the 80 person within the building will be able to see upon the mirror, when thrown down to the position shown in dotted lines in Fig. 1 of the drawings, objects from outside the building and, by turning the upper mirror, 85 the range of field will be increased, thus enabling a person within the house to see objects outside without the person being able from the outside to detect objects within. When the under mirror is not in use, it will 90 be swung up to closed position as shown in solid lines.

In the modified form shown in Fig. 4, a lens is provided through which the objects are projected upon the mirrors at the angles 95 designated by dotted lines, making it possible to view through the eye piece persons or other objects from the outside.

What I claim to be new is:—

1. An obsergraph comprising a door with 100 an opening therein, an angled hood adapted to be fastened to the door and provided with a hollow boss, an angled mirror frame having a stem journaled in said boss, a thumb wheel fixed to the stem, a mirror in said 105 angled frame, and a second mirror to re-

ceive the reflections from the first referred to mirror.

2. An obsergraph comprising a door with an opening therein, an angled hood adapted to be fastened to the door and provided with a hollow boss, an angled mirror frame having a stem journaled in said boss, a thumb wheel fixed to the stem, a mirror in said angled frame, and a second mirror adapted

to be hinged to the door and swing in contact with the edge of said hood.

In testimony whereof I hereunto affix my signature in presence of two witnesses.

GEORGE LENOX CURTIS.
